COMPUTING MACHINE

Blanchard D. Smith, Atlanta, Ga., assignor to
Scripto Manufacturing Company, Atlanta, Ga.,
a corporation of Georgia

Application March 23, 1943, Serial No. 480,221

7 Claims. (Cl. 235—145)

The invention relates to computing machines and has as an object the provision of an improved type of mechanism for computing machines shown as adapted to an adding machine, and of an improvement in keyboards for computing machines.

It is an object of the invention to secure compactness to such an extent that, when embodied as an adding machine the overall dimensions shall be roughly one-half of the dimensions of existing machines which secure the same functions.

Further objects of the invention are: to provide a keyboard for computing machines generally wherein the individual keys are substantially one-half the size of usual keys and are constructed and arranged for operation two at a time in order to provide finger space for depression of the desired key;

To provide for very simple assembly;

To provide computing machine mechanism actuated one-half by forward movement of an actuating element and the remaining half by return movement of the said element whereby movement is reduced and space conserved;

To provide a computing machine so constructed as to be possible of manufacture very largely from plastic and the necessary metal parts of which involve very little machining;

To provide a novel form of "carry one" mechanism.

Further objects of the invention will appear from the following description when read in connection with the accompanying drawings showing illustrative embodiments of the invention, and wherein:

Figure 1 is a vertical section on broken line 1—1 of Figure 2;

Fig. 2 is a detail plan view with a portion of the cover broken away;

Fig. 3 is a detail vertical section on line 3—3 of Figure 2;

Fig. 4 is a detail vertical section on line 4—4 of Figure 2 partly in elevation;

Fig. 5 is a detail section on line 5—5 of Figure 2 showing two keys depressed;

Fig. 6 is a detail plan view of certain keys illustrating an alternative key structure;

Fig. 7 is a section similar to Figure 4, taken on line 7—7 of Figure 6;

Fig. 8 is a detail section on line 8—8 of Figure 1 with parts omitted;

Fig. 9 is a detail section on line 9—9 of Figure 8; and

Fig. 10 is a detail section on line 10—10 of Figure 1.

As shown the device comprises a base plate 15 carrying a plurality of posts 16, one for each key, the posts being arranged in rows of nine each in accordance with the usual arrangement of keys

of computing machines. As shown the posts 16 are cast integral with the base 15 and for conservation of material as well as to house springs 17, the posts are formed hollow. The springs 17 may be retained in the posts by strips 18 carried by the bottom of the plate, and to support the keys 19, 21, 23 are shown as formed with an end 60 projecting through slots 61 in the posts 16.

Slidable between the posts and guided thereby 10 there are shown a plurality of keys 19, which keys are semi-circular at opposite sides thereof to fit between the posts. Carried by each key there is shown a stop member 20, for a purpose to be described. The key 21 for numeral 1 of each row is roughly one-half of the keys 19 and this key 21 15 carries a stop member 22. The key 23 for the numeral 9 has one complete cylindrical opening 24 as well as a half cylinder 25, the latter to coact with the 8 post. Other than the keys 21 and 23, the remaining keys are interchangeable with each other.

As shown in the form of the invention of Figure 2 the numeral is carried by the top of the post and is visible not only in the space between the 25 keys 19, 21, and 23, but it is intended to form the keys of transparent plastic whereby the light may have ready access to the posts and the numerals thereon as well as providing that these shall be readable through the keys, and that the keys shall not cast shadows on the numerals.

The tops of the posts 16 are of such a size that the spacing between their centers is substantially one-half of that of the usual keys of a computing machine, therefore when the mechanism is to be 35 operated for the integer 1 the finger will contact both keys 21 and 19 and when any other integer is wanted and the finger is pressed over the corresponding indicia upon the top of the post two keys will be depressed. The circular space between these two keys will have much the effect 40 and feel of the usual depression in the surface of a typewriter key.

Actuated by the keys upon their depression there is shown a plurality of rack bars 26, one 45 for each row of keys, which rack bar is moved forwardly by depression of the key and is stopped by contact of a member 27 carried by the rack bar which comes into contact with the stop 20 corresponding to the lowest numeral whose key 50 is depressed.

To actuate the rack bars 26 there is shown a rod 28 passing along each row of posts below a notch 29 in each of the keys, as clearly shown in Figure 4. For coaction with the rod 28 the 55 posts are, as shown in Figures 4 and 8, flattened at one side as at 30. The rod 28 is as shown anchored at its rear end in a plate 31, in the manner best shown in Figure 10, wherein the plate 31 is formed with a slot 32 to allow the rod to be 60 depressed, the rod being held in the upper end

of the slot by means of a spring 33. At its forward end the rod 28 is formed into a bell crank arm 34.

The arm 34 has its end 35 turned at an angle and pivoted in a plate 36 which extends across the base 15 to support the ends of all of the rods 8 of the machine. Coiled about the end 35 is a spring 37 having one end 38 acting on the arm 34 and the other end anchored to the base 39 of the plate 36. The torsion of the spring 37 is just sufficient to support the weight imposed on it, and to actuate its rack bar for return movement.

Mounted on the rod 28 is a block 40 in which there is pivoted an end 41 of a crank having an arm 42, shaft portion 43 and an arm 44, the end of the latter being turned at an angle and entering a block 45 carried by the corresponding rack bar 26.

The shaft portion 43 of the last described bell crank is pivoted at two points in springs 46 which, as shown in Figure 8, are portions of a comb plate 47 secured to the base 15 by screws 48 which also secure in place the angle shaped plate 36. The margin 49 of plate 47 is shown as turned downwardly and engaged in a groove in the base 15.

As shown in Figure 9 the portion 50 of the base 15 under the springs 46 is thinner than the portion 51 toward the end of the base. Below the spring members 46 the base is cut away upon an angle as indicated at 52 in Figure 9 to allow for the depression of the springs 46, the spring action being stiffened by support of the members 53 between the spring portions.

When any keys are depressed the first action that takes place is the yielding of the springs 46 by pressure exerted upon the shaft 43 by means of block 40. This lowers the rack 26 causing the lower rack teeth of the bifurcated end of the rack bar to leave the lower teeth of pinion 54, which teeth are, however, not freed until the upper rack bar comes into engagement with the upper teeth thereof.

Further depression of the rod 28 then causes revolution of the shaft 43 with resultant motion further to the right in Figure 1 of the rack bar causing the revolution of the pinion 54 an amount equal to one-half of the integer represented by the lowest key depressed and upon release of the keys the spring 37 causes return of the rack bar to complete the necessary revolution of the pinion 54.

It will be seen that beginning at the left of Figure 1 the members 27 are successively each one integer further spaced from the stop 20 with which they are to coact when the keys are depressed so that when the last key 20 to the right in Figure 1 is depressed the upper rack teeth will move forwardly a distance to actuate four of the teeth 54 before the rack bar is stopped by the stop member which is depressed by the number 8 key. No ratchet tooth or stop member is necessary for the 9 key as that will be operated by the full motion of the rack bar equivalent to 4½ gear teeth, the returning movement of the rack bar completing the actuation of nine teeth.

The upper end of the crank arm 44 will be seen to move on the arc of a circle as it swings. To preserve a substantially straight line motion, and to guide the rear end of the rack bars, a stationary rod 56 is provided extending crosswise of the machine and through all of the rack bars, the rack bars being formed each with a slot 57 to slide upon rods 56, which slot is as shown arcuate

in shape to cause the rear end of the rack bars to rise to follow the swinging motion of the bell crank.

The mechanical action of the rod 28 is a combination of crank action and of a lever of the third class. To compensate for spring of the rod when the power is applied close to the fulcrum of the lever, the fulcrum is provided in the form of spring 33 and the crank end 62 of rod 28 is movable in slot 32 as best shown in Figure 10, and as already described.

The number adding and registering mechanism comprises a series of devices shown in detail in Figures 1, 2 and 3 as mounted on a fixed stationary shaft 63. For numerals of each order there is shown a pinion 64 having eighteen teeth 54 which coact with the rack teeth 38 already referred to. The pinion 64 is mounted on a sleeve 65 revolvable on the rod. The mechanism further comprises a number wheel 66 for each number, shown as bearing two sets of numerals from 0 to 9 visible through the openings 66 in the cover 61.

To couple the pinion with the number wheel there is shown a coupling disk 68 formed with twenty projections ten of which project toward the pinion and extend between the teeth 54 as at 69, and the remaining ten project toward the number wheel and are loosely received respectively in ten openings 70, as at 71. The disk of coupling member 68 is shown as rigidly carried by an eccentric portion 72 of the sleeve 65. The eccentricity of the mount of the coupling is such that but one or two of the members 69 are between and in operative engagement with the teeth of the pinion at any one time, as indicated in Figure 1. The number wheel 66 will therefore be driven positively by the pinion through the coupler, but if the drive is from the coupler moving relative to the pinion, each half revolution of the sleeve, due to the difference between the number of the teeth in the pinion and the number of the members 69, will cause the number wheel to advance one numeral.

A "carry one" device is shown as comprising a plate member 73 revolvable on shaft 63 and driving sleeve 65 through projections 74 from the end of the sleeve, entering openings in the plate. To cause rotation of the plate a spring 75 in the form of a flat helix is shown, its outer turn anchored to the number wheel and its inner turn anchored to two lips 76 projecting from the plate. The spring 75 is given a moderate degree of pre-winding when the device is assembled and is additionally tensed by the adding movement of the number wheel. When the parts are in the position shown in Figure 3, the tendency of the plate 73 to rotate under urge of the spring is restrained by contact of an end of the plate with a stop 77.

To release the plate 73 for rotary movement a cam member 78 is carried by the rim of the number wheel at the "0" position which forces the end of plate 73 laterally out of contact with the stop 77. The end surface of the hub 79 of the pinion 64 is shown as tapered or rounded to permit movement laterally of the plate. Normally both ends of the plate 73 stand so close to the rim of the number wheel that the plate cannot escape from the stop 77. To permit the end of the plate 73 opposite the stop 77, to move toward the number wheel when the remaining end is moved therefrom by the cam 78, a notch 80 is formed in the rim of the wheel. There being one cam 78 and notch 80 in the number wheel, the plate is released by pressure upon opposite ends alternately.

The tension on the springs 75 in each of the number wheels of the device would cause revolution of the wheels except for engagement of the teeth of the pinions with the rack teeth of bar 26, in the case of wheels advanced from zero, or except for contact of the straight face of the cams 78 of wheels at the 0 position. To clear the machine it is therefore only necessary to move the rack bars laterally from the pinions. To provide for this movement the rack bars 26 are shown as each contacting an abutment 81' carried by rod 56, the bars each being pressed toward the abutment, the keys 19 and the pinions—forwardly of the abutments by springs 82 mounted on the rod 56 in the manner shown in Figure 1, and reacting against second abutments 83 carried by the rod.

To simultaneously move the rear ends of all bars to the left in Figure 2 in order to move the racks thereof to the right clear of the pinions, there is shown a plate 84 loosely mounted on pins 85, 86 by means of diagonal slots 87, 88, as shown in Figure 10. As illustrated the pin 85 is fast in plate 84 and works in slot 87 in plate 31, while pin 86 is fast in plate 31 and its slot 88 is formed in plate 84. A tension spring 89 reacts between plates 81 and 84 to hold each pin at an end of its slot. Wings 90, 91 are shown projecting from plate 84 through notches 92 in plate 31 and standing at opposite sides of the rear ends of each rack bar. Pressure upon clear key 93, will cause lateral movement of plate 84, wings 90 and therefore of the rear ends of the rack bars thus throwing the forward ends clear of the pinion allowing each number wheel to be revolved to the zero position.

When the number wheels are freed from control of the rack teeth of bars 26, to clear the machine, the number wheels will be revolved by springs 75 until at zero position the flat sides of cams 78 strike the plates 73. To prevent further movement by yielding of plates 73, light leaf springs 81 are provided, which springs are depressed by the ends of the plates during carry-one movement thereof.

A slightly different form of key is shown in Figures 6 and 7 wherein they are formed with semi-circular webs 94 which closely approach the similar webs of adjacent keys. In this structure the numerals instead of being carried by the tops of the posts, are shown as carried, one-half of each by adjacent webs.

The cover 67 is shown as formed with the windows 66, with elongated slots 95 through which the keys project, with an opening for clear key 93, and may be held to the base 15 in any convenient manner.

The size and spacing of key operated machines is determined by the size of the human finger and the distance between centers of the keys must accommodate all but abnormal fingers. The usual distance between such centers, if drawn to the same scale as Figure 2 of the drawings herein is indicated by the dot-dash circles on that figure, the figure being drawn to a scale greater than the actual size of the device. "Finger-tip-size" as used in the appended claims denotes this usual spacing of the keys in known key operated machines. For purposes of illustration the size and spacing of the keys is shown as one-half finger-tip-size but it is apparent some other fractional part of the normal size could be utilized.

In the operation of adding machines of the usual size it is necessary to move the upper arm in order to depress the keys in the upper half 75

of the keyboard. It is much less tiring if the operator can rest the elbow on the table and reach the necessary keys by a wrist and forearm movement. Therefore, operators are taught to use only the lower numeral keys actuating 5 and 4 for 9 and 5 and 3 or 4 and 4 for 8, etc.

With the machine of the present invention the entire keyboard may be reached with purely wrist or wrist and forearm movement. The elimination of a mental calculation improves accuracy, and saves half the manipulating time of the operator on adding the larger numerals.

The reduction in size resulting from the improvement in keyboards with the improvement in operating mechanism enables the provision of a machine that may be easily carried in a usual coat side pocket.

Minor changes may be made within the scope of the appended claims without departing from the spirit of the invention.

I claim:

1. A keyboard for computing machines comprising: upstanding key guides spaced on centers separated a distance of substantially one-half finger-tip size; keys each comprising two connected oppositely open-sided shells each shell partially embracing one of two adjacent guides; and indicating numerals centered between each two adjacent keys.

2. The combination of claim 1 wherein the numerals are carried by the ends of said guides.

3. The combination of claim 1 wherein said shells are each upwardly closed by a web, and the numerals are carried, one-half of each by adjacent webs which form a finger-contacting surface.

4. The combination of claim 1 wherein the upper ends of said shells are open and the numerals are carried by the exposed ends of the guides.

5. A keyboard for key-actuated machines for use of adult operators, comprising: a plurality of rows of keys spaced not substantially more than one-half finger-tip clearance apart in each row; at least a portion of each key having only operating clearance from a portion of an adjacent key; indicating characters for said keys; said indicia, intermediate the first and last key of each row, common to two of said keys.

6. A keyboard for key-actuated machines for use of adult operators, comprising: upstanding key guides spaced on centers separated a distance of substantially one-half finger-tip size; keys each comprising two connected and oppositely extending guide members, each member slidably engaging one of two adjacent key guides; and indicating characters centered between each two adjacent keys.

7. A keyboard for key-actuated machines for actuation by finger tips of adult operators, comprising: a plurality of rows of nine keys each; the intermediate keys of each row spaced on centers not substantially more than one-half finger tip size apart; said intermediate keys comprising finger contacting portions extending in opposite directions toward like portions of adjacent keys; indicia for said intermediate keys each common to two thereof; and guide means for said keys common to the oppositely extending portions of said finger contacting portions; whereby a finger tip pressed over said indicia will operate two adjacent keys and the total length of said rows will be substantially one-half of the length of a row of nine individually finger operated keys.
